US00D468134S

(12) **United States Design Patent** (10) Patent No.: **US D468,134 S**
(45) Date of Patent: ** Jan. 7, 2003

(54) **STAND FOR TELEVISION RECEIVER**

D445,098 S 7/2001 Matsuoka et al.
D460,056 S * 7/2002 Niitsu D14/126

(75) Inventor: **Yuji Oikawa**, Tokyo (JP)

OTHER PUBLICATIONS

(73) Assignee: **Sony Corporation**, Tokyo (JP)

Catalog "Sony, Flat Panel Television, KZ-42HS500", p. 2,
Sony Corporation (Jun. 2001).

(**) Term: **14 Years**

* cited by examiner

(21) Appl. No.: **29/157,552**

Primary Examiner—Cathron C. Brooks
(74) Attorney, Agent, or Firm—Rader, Fishman & Grauer,
PLLC

(22) Filed: **Mar. 22, 2002**

(57) **CLAIM**

(51) LOC (7) Cl. **06-04**

The ornamental design for a stand for television receiver, as
shown and described.

(52) U.S. Cl. **D6/466**

DESCRIPTION

(58) **Field of Search** D6/630, 436, 449,
D6/474, 477, 478, 479, 470, 466; D14/126,
133, 239; 211/41.14, 42, 43, 133.1, 205;
312/7.1, 7.2, 9.1, 111, 249.6, 249.8, 249.13

FIG. 1 is a perspective view of a stand for television receiver
showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
